WEIGHT FOR BARBELL

Forrest H. James, Jr., Opelika, Ala., assignor to Diversified Products Corporation, Opelika, Ala., a corporation of Alabama

Filed Sept. 16, 1963, Ser. No. 76,608

Term of patent 14 years

(Cl. D34—5)

FIG. 1

FIG. 2

FIG. 3

FIG. 4

FIG. 5

FIG. 1 is a side elevational view of a weight for barbell showing my design.

FIG. 2 is a plan view of the weight for barbell shown in FIG. 1.

FIG. 3 is a cross-sectional view taken along line 3—3 in FIG. 1.

FIG. 4 is a cross-sectional view taken along line 4—4 in FIG. 1.

FIG. 5 is a perspective view of the weight for barbell shown in FIG. 1.

I claim:

The ornamental design for weight for barbell, substantially as shown.
